UNITED STATES PATENT OFFICE.

FRANK WHITE, OF NEW YORK, N. Y.

CORNER-BEAD.

No. 902,632.

Specification of Letters Patent.

Patented Nov. 3, 1908.

Application filed December 12, 1907. Serial No. 406,180.

To all whom it may concern:

Be it known that I, FRANK WHITE, a citizen of the United States, residing at New York, borough of Manhattan, county of New York, and State of New York, have invented certain new and useful Improvements in Corner-Beads, of which the following is a specification.

This invention relates to improvements in corner beads such as are used by plasterers in the construction of plastered walls, and also in the clips or anchor plates for holding such corner beads in position.

The objects of the invention are to provide a clip and a corner bead in which the clip can be quickly and properly applied to the corner bead without the use of any other instrument than the hands, also to reinforce and strengthen the corner bead at the point of attachment of the clip, and also to so construct the clip that it will hold its position on the bead until it is nailed in position.

Further objects are to provide reliable and substantial corner beads and clips which may be practically used with the least possible expense and trouble.

As is well known, corner beads, sometimes termed "corner strips", are used in the construction of plastered walls to form outlines or guides for the trowel, anchorage places for the mortar, and protection for the finished work where corners, arrises, sweeps, angles, and arches occur.

These being some of the ends in view, my invention consists of certain features of construction and combinations of parts to be hereinafter described and then claimed, with reference to the accompanying drawings showing a desirable form of the invention, and in which—

Figure 1 is a perspective view showing the improved corner bead and its clip or anchor plate applied; Figs. 2 and 3 are transverse sections on lines 2—2 and 3—3, Fig. 1, respectively; Fig. 4 is a perspective view of the clip or anchor plate, and Fig. 5 is a modified form of corner bead.

Referring to the drawings, the improved corner bead in its preferred form will be found to comprise a metallic strip bent along the longitudinal axis in such wise as to provide a bead proper or front edge *a* which may be rounded as shown or sharper, and longitudinally extending diverging or spread wings *b*, each of said wings being reinforced

along the rear portions by means of narrow lips *c*, which are bent outwardly and forwardly towards the bead proper or front edge *a*, and which are spaced a suitable distance away from the body of the wings. The angle formed by each lip and the contiguous side of the bead is less than a right angle. Such a construction of corner bead provides suitable means for attaching the form of clip disclosed herein and for supporting the corner bead in proper position, without the use of tools. The corner bead may have a cross section similar to Fig. 5.

In the best form of the invention the reinforcing means *c* at both sides extend in substantially diverging planes with the bead-proper *a* at the line of convergence.

The improved clip or anchor plate, shown more particularly in Fig. 4, consists of a shank *d*, two projections *e* and *f* at one end of said shank separated from each other by means of a gap *g* formed by cutting out the end of the shank, said projections being bent up and formed diversely, that is to say, the projection *e* at one edge of said shank is bent out of the plane of the shank so that its main portion extending away from the shank will be parallel thereto, while the other projection *f* has a hook-end *f'* which is located on the same side of the shank as is the projection *e*. Said form, construction and arrangement of the projections *e* and *f*, which are the ones preferably resort to, adapt the clip for engagement with opposite sides of a wing of the corner bead.

To engage the clip with the corner bead, the lip portion *c* of the bead is received in the gap *g* and the clip is then turned sidewise causing the hook-end *f'* of projection *f* to take over the lip *c* at one side of a wing of the bead while the other projection *e* bears against the opposite side of said wing. The said projections *e* and *f*, when thus interlocked with the reinforced edge of the bead, prevent the bead from being pulled away from the clip and also prevent it from moving laterally in either direction. The inward movement of the bead towards the clip is taken care of and prevented by means of a little spur of metal *h* which is struck out of the projecting portion *f* and projects away from the same side of the shank as does the hook *f'*, and forms an abutment for the rear edge of the bead.

When a suitable number of clips such as

- those herein described are arranged at proper points along the reinforced edges of the improved corner bead, the bead is ready to be set in position by driving nails or passing other suitable fastenings through holes previously formed in the clip. Of course it is not absolutely necessary to form the holes in the clips, but this is the better practice.
- 10 Obviously other forms of corner bead and clip within the scope and spirit of my invention will suggest themselves to those skilled, and I do not therefore limit myself to the form, construction or arrangement shown.
- Having thus described my invention, what I claim as new therein and desire to secure by Letters Patent is:
1. A corner bead, consisting of a metallic strip having longitudinally extending spread wings, both of which wings are reinforced in substantially diverging planes with the front bead proper at the line of convergence, the said reinforcing means also forming an angle with the bead which is less than a right angle.
2. A corner bead, consisting of a metallic strip having longitudinally extending spread wings, both of which wings are reinforced along the longitudinal edges in substantially diverging planes, with the front bead proper at the line of convergence, the reinforcing means also forming an angle with the contiguous sides of the bead which is less than a right angle.
3. A corner bead, consisting of a single strip of metal substantially angular in cross section to provide wings, and lips bent up from said wings and extending toward the front bead proper to provide a longitudinal reinforce for each of the wings, each of said lips forming an angle with the contiguous side of the bead which is less than a right angle.
4. A corner bead, consisting of a strip of metal having a front bead proper and a longitudinal narrow rear lip spaced away from the strip and extending towards the front bead proper, said lip forming an angle with the adjacent side of the bead which is less than a right angle.
5. A corner bead, consisting of a metallic strip having longitudinally extending spread wings, both of which wings are reinforced on their outer sides, the reinforcing means also forming an angle with the sides of the bead which is less than a right angle, combined with a clip or anchor plate in engagement with the reinforced portions of the bead.
6. A corner bead, consisting of a single strip of metal substantially angular in cross section to provide wings, and means for reinforcing both of said wings on their outer sides, the reinforcing means also form-

ing an angle with the sides of the bead which is less than a right angle, combined with a clip or anchor plate in engagement with the reinforced portions of the bead.

7. A corner bead, consisting of a single strip of metal substantially angular in cross section to provide wings, and lips bent backwardly from said wings and toward the front bead proper to provide a longitudinal reinforce for each of the wings, said lips forming an angle with the sides of the bead which is less than a right angle, combined with a clip or anchor plate in engagement with the reinforced portions of the bead.

8. A corner bead, consisting of a strip of metal having a front bead proper and a longitudinal narrow rear lip spaced away from the strip and extending towards the front bead proper, said lip forming an angle with the contiguous side of the bead which is less than a right angle, combined with a clip or anchor plate in engagement with the reinforced portions of the bead.

9. A corner bead consisting of a strip of metal substantially angular in cross section to provide wings, and lips bent up from said wings to provide a longitudinal reinforce for each of the wings, combined with a clip comprising a shank having beyond it separate projecting means positively interlocking with both sides of the reinforced portion of a wing, and an abutment separate from said interlocking means for the outer edge of the said wing, for substantially the purposes set forth.

10. A corner bead consisting of a strip of metal substantially angular in cross section to provide wings, and lips bent up from said wings, to provide a longitudinal reinforce for each of the wings, combined with a clip comprising a shank having means to interlock with the reinforced portion of a wing, and a separate abutment at one edge of the shank for the edge of said reinforced portion of the said wing, said clip being readily detachable from and shiftable along the reinforced portion of said wing, for substantially the purposes set forth.

11. In a clip for corner beads, a shank, having means to interlock with a bead, and comprising two projections only for engaging opposite sides of the rear edge of a bead, the said projections being separated edge-wise by a relatively wide gap, and, separate therefrom, an abutment for the rear edge of a bead.

12. In a clip for corner beads, a shank, having two projections separated by a gap and for engaging the sides of a bead, one of said projections being bent out of the plane of the shank and its longer main portion extending substantially parallel with the shank, and the other projection having a hook-end bent back towards the shank, the said pro-

- jections being arranged to receive a portion of the bead close to their connection with the shank.
13. In a clip for corner beads, a shank, having two projections separated by a gap and for engaging the sides of a bead, one of said projections being bent out of the plane of the shank and extending substantially parallel therewith, and the other having a hook-end bent back towards the shank, and an abutment for the rear edge of a bead.

14. In a clip for corner beads, a shank, having a projection provided with a hook-end bent back towards the shank, and additional means coöperating therewith to engage and support a bead.

Signed at New York, N. Y., this 10th day of December, 1907.

FRANK WHITE.
